UNITED STATES PATENT OFFICE.

OSWALD E. WINGER, OF JOLIET, ILLINOIS.

DESIGN FOR A WINDOW-LIGHT.

SPECIFICATION forming part of Design No. 29,113, dated July 26, 1898.

Application filed June 16, 1898. Serial No. 683,630. Term of patent 7 years.

To all whom it may concern:

Be it known that I, OSWALD E. WINGER, a citizen of the United States, residing at Joliet, in the county of Will and State of Illinois, 5 have invented and produced a new and original Design for Window-Lights, of which the following is a specification, reference being had to the accompanying drawings, forming part thereof.

10 Figure 1 is a perspective view of a glass pane, showing my new design. Fig. 2 is an end view thereof. Fig. 3 is a face view thereof.

The design consists of the window-light *a*, having a series of cavities *b b* extending into 15 the interior from one edge and a series of cavities *c c* extending into the interior from the opposite edge, the cavities extending alternately from opposite edges of the window-light between the faces thereof.

The essential or material feature of the design is the window-light provided with the cavities extending longitudinally into the interior from the opposite edges of the window-light and lying between the faces of the window-light. 20

Having described my invention, what I claim as new, and desire to secure by Letters Patent, is—

25 The design for a window-light as herein shown and described.

30 In witness whereof I have hereunto subscribed my name in the presence of two witnesses.

OSWALD E. WINGER.
